UNITED STATES PATENT OFFICE.

GEORGE A. SIMS, OF ERIE, PENNSYLVANIA, ASSIGNOR TO THE SIMS COMPANY, OF ERIE, PENNSYLVANIA.

REVERSIBLE HEATING OR COOLING APPARATUS.

Application filed August 26, 1922. Serial No. 584,559.

To all whom it may concern:

Be it known that I, GEORGE A. SIMS, a citizen of the United States, residing at Erie, in the county of Erie and State of Pennsylvania, have invented certain new and useful Improvements in Reversible Heating or Cooling Apparatus; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to reversible heating and cooling apparatus, and the object thereof is to provide means whereby a heat or cold bearing fluid is caused to flow through a plurality of tubes which extend through a chamber which contains the fluid to be heated or chilled, and in providing means within said chamber adapted to cause the fluid to be heated or chilled to flow in successive and alternate transverse directions with relation to said tubes as it progresses from the intake to the outlet of said chamber.

To accomplish this I provide a hollow cylinder in which I place a series of discs transversely within the cylinder, these discs being provided with spiral flanges which space the discs apart. Each alternate disc is provided with a central opening, and the next adjacent disc has a portion of its periphery cut away thus forming a notch therein, so that the fluid to be heated or cooled passes through said notch and then in a spiral course to the central portion of the chamber, and then through the central opening in the next disc, and then in a spiral course to the outer portion of the chamber, and so on in alternately reversed spiral directions until the exit from said chamber is reached.

These and other features of my invention will be hereinafter pointed out, and are illustrated in the accompanying drawings, in which:

50 Figure 1, is a side elevation of my reversible heating and cooling apparatus, with a portion of the shell broken away.

55 Figure 2, is a vertical section of a fragment thereof showing the construction of the ends thereof.

Figure 3, is a transverse section thereof on the line 3—3 in Figs. 1 and 2.

Figure 4, is a like view on the line 4—4 in Fig. 1.

Figure 5, is a like view on the line 5—5 60 in Fig. 1.

Figure 6, is an edgewise elevation of one of the discs which form divisions within the cylinder shell.

Figures 7 and 8 are side elevations of two 65 of said discs turned from each other showing the meeting edges of the spiral flanges thereon.

Figure 9, is an edgewise elevation of one of the end or terminal discs, having the 70 spiral flange on one side thereof widened as hereinafter described.

In these drawings A indicates a cylindrical shell having flanges out-turned at each end thereof. Within this shell A I 75 place a plurality of discs B and B', the discs B being cut away as shown at b in Figs. 5 and 8, and the alternate discs B' having a central opening b' therethrough as shown in Figs. 4 and 7.

These discs B and B' are provided with identical spiral flanges b² on their adjacent faces, which space said discs apart as shown in Figure 1, but also form spiral passages between said discs from the wall of the cylinder inwardly to its axis.

At each end of the cylinder A there are formed inlet and outlet openings a and a' by means of which the fluid to be cooled or heated is introduced into and discharged 90 from the said cylinder.

The discs B which terminate the series at each end of the cylinder are provided with a widened flange b³ which will space the first disc B at each end of the cylinder A sufficiently inward from the end thereof to provide a chamber into which the inlet and discharge openings a and a' enter.

The discs B and B' are provided with holes b⁴ through which tubes C pass, the 100 ends of which tubes are secured in plates D which fit against the flanged ends of the cylinder A and against the plates D at each end of the cylinder a header chamber E is secured which encloses therein the ends of all 105 the tubes C. These header chambers E are provided with inlet and outlet pipes F and F' by means of which the heating or cooling fluid is introduced and passed through the pipes C.

- In operation the fluid to be treated is introduced into the cylinder A through the inlet a and caused to circulate therethrough and out of the discharge opening a' during which it transversely passes the tubes C in alternately reversed spiral paths formed between the discs B and B' by means of the spiral flanges b². The heating or cooling medium is introduced in the header E through the inlet pipe F and it travels therefrom through the pipes C to the opposite header E and out through the discharge pipe F'. It will be obvious that the continuance of this operation of my improved apparatus will effectually produce a substantially equalization of temperature between the fluid introduced into the headers E and tubes C, and that circulated through the cylinder A.
- Having thus fully described the construction and operation of my invention, what I claim as new and desire to secure by Letters Patent is:
1. In an apparatus of the class described, a casing having inlet and outlet openings at opposite ends thereof, a series of transverse walls therein, each alternate wall having a central opening therethrough, and the other

alternate walls having a notch cut out of the periphery, spiral flanges on the adjacent faces of said transverse walls, a plurality of longitudinal tubes passing through said casing and through said transverse walls and secured in plates at the ends of said casing, and header chambers on the ends of said casing covering the ends of said tubes.

2. In an apparatus of the class described, a casing having inlet and outlet openings adjacent to the ends thereof, a series of tubes passing longitudinally through said casing and secured in the end walls thereof, a series of transverse walls in said casing, and spiral flanges on said transverse walls spacing the same apart.

3. In an apparatus of the class described, a casing having inlet and outlet openings adjacent to the ends thereof, a series of tubes passing longitudinally through said casing, means within said casing to cause longitudinal and alternately reversed spiral flow of fluid through said casing, and headers on the ends of said casing.

In testimony whereof I affix my signature.

GEORGE A. SIMS.
